FIRE CONTROL APPARATUS

Fred A. Woodworth, Minneapolis, Minn.

Application March 24, 1943, Serial No. 480,300

2 Claims. (Cl. 169—2)

1

This invention relates to fire control apparatus. It is an object of my invention to provide improved means for storing fire extinguishing fluids and more particularly highly volatile fluids and for releasing such fluids at predetermined temperatures caused by fires.

More specifically it is an object to provide a frangible container for extinguishing fluid and means operable at pre-determined temperatures for breaking the container and releasing the fluid.

Another object of the invention is to provide means for insulating the container against heat so that highly volatile extinguisher fluids will not produce leaks in the container or cause it to burst prematurely.

Still another object of the invention is to provide means for catching the fluid from the broken container and conveying it to any desired point remote from the container.

A further object of the invention is to provide a frangible container and means for breaking the same in combination with an alarm device actuated by the container breaking means.

Another object of the invention is to provide spring actuated container breaking means wherein in the breaking means is held in inoperative position by a device which includes a fusible element which can be remotely positioned from the container and breaking means plus means for conveying the fluid from the container to the vicinity of the fusible element.

These and other objects and advantages of the invention will more fully appear from the following description made in connection with the accompanying drawings, wherein like reference characters refer to the same parts throughout the views, and, in which:

Fig. 1 is a plan view of an embodiment of my invention showing the container support and breaking means;

Fig. 2 is a longitudinal vertical section through the device of Fig. 1;

Fig. 3 is a diagrammatic view of the device shown in Figs. 1 and 2 with fluid conducting conduits, a cable having thermal element connections therein and a cable connection to a remotely positioned alarm device;

Fig. 4 is a plan view of an alarm device used in conjunction with the extinguisher unit;

Fig. 5 is a section on the line 5—5 of Fig. 4;

Fig. 6 is a side elevation of a modified form of extinguisher unit with portions broken away and in section; and

Fig. 7 is a bottom plan view of the structure shown in Fig. 6.

2

In Figs. 1 and 2 there is shown a frame made up of side members 8 and 9, a plurality of substantially rectangular frame members 10 which are connected to the side members 8 and 9, and a right-hand end member 11 which connects the right ends of the side members 8 and 9. Suitable longitudinal reinforcing members such as the strap 12 may also be provided to connect the rectangular members 10 for added strength. 10 Connected to the side members 8 and 9 are mounting brackets 13 which permit the framework to be supported from the ceiling in a room.

Mounted in the cage-like framework just described is a casing 14 which may be formed of 15 sheet metal in the shape of a can. As viewed in Fig. 2, the left-hand end of the casing is open and the right-hand end is provided with an end disc 15 having a central opening 16 therein. The casing 14 is secured at its lower side portion by 20 means of bolts 17 to the end frame members 10 and one of the longitudinal braces 12. The lower portion of the casing end 15 is provided with a drain opening 18.

The interior of the casing 14 is lined with a 25 suitable insulating material 19 about its circular side wall and across the opening 16. The insulating material is preferably an easily breakable fibrous material such as asbestos sheeting. The left-hand end of the container 14 is provided 30 with a removable cap or cover 20 which is also lined with an insulating material and at its inner central portion the insulation is built up as at 21 to provide a cushioning pad. A movable pin 22 extends between a pair of spaced brackets 8' and 35 9' on the rear of the outer frame to releasably lock the cover 20 on the end of the can 14.

Positioned within the heat insulating casing 14 is a frangible container 23 in the form of a glass jug which is adapted to hold fire extinguisher fluid such as carbon tetrachloride. However, any suitable and preferably volatile extinguishing fluid can be used. Mounted on the frame end member 11 is a bracket 24 which is spaced outwardly from said end member 11 intermediate its 40 ends and forms with said end member a bearing unit for slidably supporting a plunger 25. The left-hand end of the plunger 25 is provided with a hardened steel point 26 and immediately behind this is a generally conical head 27. A spring 28 on the plunger 25 is interposed between the rear of the head 27 and the frame end member 11, and tends normally to urge the plunger toward the frangible container 23.

The right-hand end of the plunger 25 is provided with a stop flange 31 to limit its move-

ment toward the left and said end of said plunger is also provided with an opening or eye 32. Running through the eye 32 is one end of a cable 33 which may be anchored at its other end to keep the plunger 25 retracted.

Beneath the casing 14 and frangible container 23 is a collector pan 34 supported from the left and right-hand rectangular frame elements 10 by means of straps 35 and 36. The strap 36 is somewhat longer than the strap 35 and for that reason the pan 34 slants toward its right-hand end. A conduit 37 is connected to the lower right-hand end of the pan 34. A stopper 38 normally lies in the end of the conduit 37 to prevent dirt from entering the conduit when the extinguisher is not in use. The stopper 38 is connected to a loop or link 39 which is freely slideable on a rod 40 which extends inwardly from the right-hand end of the pan above the bottom thereof. The stopper 38 is also connected by a wire or cord 41 to the plunger head 27 so that when the plunger is released and forced to the left by the spring 28 to break the jar 23 and release extinguisher fluid therefrom the wire 41 will pull the stopper 38 out of the end of the conduit 37. Thereupon fluid will flow from the broken container 23 and through the aperture 18 and casing 14 to the collector pan 34 and thence to the conduit 37 where it flows to any predetermined or desired point.

An electrical switch 42 is mounted on a block of insulating material 43 which is secured to the frame side member 9. The switch is provided with binding posts 44 and a reciprocating contact plunger 45. The details of the switch are not shown since it may be of any conventional type such as an automobile caution light switch with a reciprocating contact plunger. A reciprocating rod 46 is slidably mounted on a bracket 47 which is also secured to the frame side member 9. The rod 46 has a block of insulating material 48 on its end and a spring 49 is interposed between the insulating block 48 and a side of the bracket 47. The right-hand end of the rod 46 has connected thereto a cable or wire 50 which extends through the aperture 32 in the right-hand end of the plunger 25 and has its opposite end anchored to an eye bolt 51 on the frame end member 11. Thus when the main plunger 25 is released and urged to the left by the spring 28 the rod 46 will move to the left and engage the switch plunger 45 to close the switch. This switch can be connected to any suitable electrically operated alarm device. In the diagrammatic view, Fig. 3, the cable 33 which is connected to the right-hand end of the plunger 25 may extend to any suitable point and in the diagram it is shown to extend through a wall 52 and have its end anchored in a flue or air duct 53. At spaced points along the cable, fusible elements 54 may be provided so that excessive heat will melt the fusible elements thus breaking the cable connection in the event of fire and releasing the plunger 25 so that it will enter the casing 14 through its end opening 16 and break the frangible container 23 to release the extinguisher fluid. The insulating material covering the opening 16 in the casing 14 is sufficiently weak to be easily broken by the plunger point 26 and head 27.

In the flue or air duct 53 I provide a fusible link 55 which is a link in the cable 33. The branch of the conduit 37 leads to the collector pan 34 so that in the event of a fire in the air duct 53 the link 55 will melt releasing the plunger 25 thereby breaking the container 23 and permitting extinguisher fluid to flow from the broken container 23 through said conduit 37 into the interior of the air duct 53.

From the foregoing description it will be seen that I have provided automatic fire control means which includes an extinguisher containing a fluid that is released by the melting of a fusible element which restrains a spring actuated device provided to fracture the container of the fluid. At the same time means is provided for closing alarm circuits and for actuating mechanical alarms at points remote from the extinguisher itself. The alarm actuation is dependent upon and set off by the mechanism which breaks the container for the fire extinguishing fluid. Means is provided for releasing fluid and conducting it into the interior of a flue or air duct.

One important advantage of the apparatus is that it can be refilled after use by merely securing a glass or other breakable container of a size to approximately fit the interior of the metal casing and filling the container with a liquid such as carbon tetrachloride which is easily obtainable. It is unnecessary to purchase specially prepared refill containers. All that is required is that the container be tightly sealed so that the carbon tetrachloride will not leak out. As a precaution against leakage or bursting of the glass container due to tendency of the liquid to expand and volatilize the container casing is heat insulated.

In order to prevent soot and dirt from entering the discharge end of the conduit 56 where it is positioned in the interior of a flue or air duct it is preferred that the end of said conduit be closed by an easily melting substance such as wax which will melt and drop off at excessive temperatures.

While I have described the apparatus in connection with a building structure where it is best adapted for use, it could, of course, be used without the pan and distributor conduits in vehicles such as large vans.

It will, of course, be understood that various changes may be made in the form, details, arrangements and proportions of the various parts without departing from the scope of my invention.

What is claimed is:

1. Fire control apparatus comprising, a container for a fire extinguishing fluid, temperature controlled means movable to release fluid from said container, a pan beneath said container for collecting the released fluid, and a conduit connected to said pan for conveying the fluid to a remote point.

2. The structure in claim 1, and conduit closure means normally closing the inlet of said conduit and connected to said fluid release means, said conduit closing means being movable with said release means to open said conduit and permit the flow of fluid thereinto.

FRED A. WOODWORTH.
